United States Patent Office.

SAMUEL B. SEXTON, OF BALTIMORE, MARYLAND.

Letters Patent No. 97,970, dated December 14, 1869; antedated November 23, 1869.

BASE-BURNING FIRE-PLACE HEATER.

The Schedule referred to in these Letters Patent and making part of the same.

I, SAMUEL B. SEXTON, of the city of Baltimore, in the State of Maryland, have invented certain new and useful Improvements in Base-Burning Fire-Place Stoves, some of which improvements are applicable to heating-apparatus of other kinds.

My said invention is described as follows:

Nature and Objects of the Invention.

This invention relates chiefly to what are known as magazine fire-place heaters, being a class of heating-stoves which is adapted to be set partially within the chimney or fire-place, to heat air for the warming of apartments above that in which the stove is placed, and to receive their fuel through a magazine or chamber, at the base of which the combustion takes place. Some of my improvements are, however, applicable to stoves and fire-places of other kinds, as will be hereinafter explained.

My invention consists, first, in constructing the stove with a magazine whose walls are exposed directly to the atmosphere, a feed-door or conductor for supplying the magazine with fuel, and a separate valve, by which gases are prevented from passing upward through the magazine while the stove is in full operation, but may be carried off into the discharge-flue before opening the feed-door for the introduction of fuel; second, in combining, with the exposed magazine, reflexed pipes or columns for conducting gases to the lower part of the stove from the combustion-chamber beneath or around the lower part of the magazine; third, in a peculiar combination and arrangement of flue-pipes, as hereinafter set forth; fourth, in a shield or screen, adapted, as hereinafter described, to be secured in front of the fire-place or stove; fifth, in a peculiar construction of the external walls of the stove.

Description of the Drawings.

In the accompanying drawings—

Figure 1 is a front elevation of the stove with the shield removed.

Figure 2 is a side elevation of the stove, with the shield and the chimney in section.

Figure 3 is a front elevation, showing the shield in position.

Figure 4 is a vertical section, in the plane indicated by the line $z z$, fig. 2.

Figure 5 represents a vertical section at $y y$, fig. 1, the plane of section being at right angles to that shown in fig. 4.

Similar letters of reference indicate corresponding parts in the several views.

A represents the fuel-magazine, the walls of which are exposed to the atmosphere, and are preferably made to flare upward, as shown.

The lower part A' of the magazine extends down-

ward within the combustion-chamber B, in the customary manner.

C is the grate;

D, the ash-pit; and

D', an ash-drawer or pan.

The walls of the combustion-chamber B are provided with the customary illumination-windows $b b$.

E E are flue-columns or pipes rising from the fire-chamber B, bent over at top, and descending to the flue-chamber F, at the base.

G G are flues or pipes rising from the lower chamber F to the upper flue-chamber H, which communicates with the discharge-flue I, as shown in fig. 5.

J is a door or cover closing the opening through which fuel is supplied to the magazine A.

The said opening may be made directly in the external wall of the magazine, or a conducting-tube or funnel, P, may be employed, as shown in fig. 5.

In the top of the magazine is formed a valve, K, which may be opened to afford more free and direct draught in kindling the fire, and must be opened to discharge gases from the magazine before opening the door J for the introduction of fuel.

The pipes E E are provided with the customary dampers e e.

Doors f f afford access to the flue-chamber F, for the purpose of cleaning the same, or checking the fire, or ventilating the apartment.

L L are various parts of the external casing, within which, around and above the stove, is the chamber in which air is heated to be carried up through the chimney M to apartments above.

The front part of the stove is surmounted by a crown-plate, N, which, partially covering the space between the stove and the casing L, makes a neat and ornamental finish, and, being perforated, allows the escape of heated air into the room.

O represents an ornamental shield or screen, which may be employed to cover the front of stoves of cheap and plain exterior, or to cover the fire-place in summer-time.

The said shield or screen is perforated, as shown at o o, to permit the passage of air into the room, and is preferably formed with one or more doors, to afford access to the stove without removing the screen.

It may be secured in position by means of projecting studs, fitting in holes q q in the front of the stove, or it may be made in two pieces, and hinged at the sides to either the stove, or the frame, or casing, the hinges being so constructed as to permit the screen to be lifted off and removed at pleasure, or to slide back into the rear or interior, if desired.

Between the walls of the combustion-chamber B and the cylindrical fire-pot B' below it, I form a shoulder, v, as shown in the drawings. This is of great ad-

vantage in various ways. The windows are thereby removed to a greater distance from the burning fuel, and the combustion is rendered more active and complete.

Operation.

To start the fire, or to discharge gases from magazine, the valve K, at the top of magazine A, is opened.

When the fire is burning, and the magazine supplied, the valve is closed. The products of combustion then pass from the chamber B, through the pipes E E, to the base of the stove, and thence upward, through one or more pipes, G G, to the upper chamber H, which communicates with the discharge-flue I.

The checking of the draught may be effected by closing dampers e in the pipes E, or by opening the doors f f, to admit air to the flues at the base of the stove, which latter arrangement affords effective ventilation.

A drawer may be employed, to receive the ashes and close the ash-pit in customary manner, or, if preferred, a common pan may be used, and the ash-pit closed by doors.

Claims.

I claim, as my invention—

1. An exposed magazine, in combination with a valve for discharging gas therefrom, and a separate door or conductor for introducing fuel.

2. An exposed magazine, in combination with pipes or columns for conducting the gases from the combustion-chamber beneath or around the lower part of said magazine to the flue-chamber at the base of the stove.

3. The combination and arrangement of the pipes E E, G G, I, and chambers F H, substantially as set forth.

4. The shield or screen O, constructed either with or without perforations, or a door or doors, or both, substantially as set forth.

5. In a fire-place stove, the shoulder between the illuminated walls and the cylindrical fire-pot, arranged, relatively to the flues E, substantially as set forth.

SAMUEL B. SEXTON.
